(57) **CLAIM**

We claim the ornamental design for the spine region of a binder, as shown and described.

DESCRIPTION

FIG. 1 is a front perspective view of a spine region of a binder in a closed configuration showing our new design.

FIG. 2 is a back perspective view including the spine region of FIG. 1.

FIG. 3 is a front elevational view of the binder including the spine region of FIG. 1.

FIG. 4 is a back elevational view of the binder including the spine region of FIG. 1.

FIG. 5 is a top-edge plan view the binder including the spine region of FIG. 1.

FIG. 6 is a bottom-edge plan view the binder including the spine region of FIG. 1.

FIG. 7 is a left-side elevational view the binder including the spine region of FIG. 1.

FIG. 8 is a right-side elevational view the binder including the spine region of FIG. 1; and,

FIG. 9 is an elevational view of the outside surface of the binder including the spine region of FIG. 1 with the binder in an open configuration.

The dotted lines are for illustrative purposes only and form no part of the claimed designs.
